ATTORNEY

UNITED STATES PATENT OFFICE.

ORA A. COLBY, OF IRWIN, PENNSYLVANIA, ASSIGNOR TO WESTINGHOUSE ELECTRIC & MANUFACTURING COMPANY, A CORPORATION OF PENNSYLVANIA.

ELECTRIC HEATER.

Application filed September 2, 1922. Serial No. 585,844.

To all whom it may concern:

Be it known that I, ORA A. COLBY, a citizen of the United States, and a resident of Irwin, in the county of Westmoreland and State of Pennsylvania, have invented a new and useful Improvement in Electric Heaters, of which the following is a specification.

My invention relates to electric heaters, and particularly to electric air heaters.

10 One object of my invention is to provide a relatively simple, rugged and compact structure for an electric air heater.

Another object of my invention is to provide a structure for an electric heater that 15 shall permit of easily and quickly changing the resistor units in case of repairs or when it is desired to change the amount of energy translated into heat.

In practicing my invention, I provide a 20 casing having a base upon which are operatively secured two spaced, parallel, and co-extensive insulating bars. Flat terminal members are clamped between the two parallel bars adjacent to the ends thereof and 25 extending therebeyond. A plurality of resilient terminal clips are secured against each of the terminal members in back-to-back relation. A plurality of refractory resistor members are supported in spaced 30 relation by the resilient terminal clips.

In the single sheet of drawings,

Figure 1 is a view, in longitudinal section, of a device embodying my invention, taken on the line I—I of Fig. 3;

35 Fig. 2 is an end view thereof; and

Fig. 3 is a view in lateral section thereof, taken on the line III—III of Fig. 1.

An electric heater, designated generally by the numeral 11, comprises a suitable base 40 12 which may be of any refractory material. A cover member may comprise a bottom plate 13 suitably secured against one edge of the base plate 12 and a top cover portion 14 having one edge thereof operatively engaging 45 the other edge of the base plate 12, and having its other edge operatively engaging one edge of the plate 13. A plurality of members 15, of substantially L-shape, may be provided to more securely hold the cover 50 members 13 and 14 against the base plate 12.

Upon one surface of the base plate 12 there are mounted a plurality of flat bars 16 of suitable insulating material such as asbestos lumber, located in spaced, parallel, co-extensive relation and having a narrow

edge thereof operatively engaging the base plate 12. Securing means 17 may be provided to hold the bars 16 against the base plate 12. Metallic terminal members 18 are located between the two bars 16 adjacent to the ends thereof and extending therebeyond and may be held in their proper operative positions by a plurality of rivets 19. A plurality of resilient terminal clips 21 are secured, in back-to-back relation, 60 against each of the terminal members 18 by rivets 22.

A plurality of refractory resistor rods 23, having metallic tubular terminal members 24 secured thereto at the ends thereof, 70 are operatively supported by the spring clips 21. The terminal members 24 are not a necessary part of the resistor members, but where the energy translated into heat becomes relatively large, the use of such 75 metallic terminal members with a carbonaceous resistor rod is advisable in order to prevent overheating of the ends of the rod. The terminal clips 21 not only support the resistor rods but also conduct current there- 80 to and permit of easily and quickly removing and replacing the rods whenever necessary.

An insulating bushing 25 may be provided 85 in the end wall 26 of the heater 11, to permit of leading therethrough supply-circuit conductors, not shown, one of which may be connected to the terminal bar 18 at the right-hand end of the heater and the other of 90 which may be connected to the left-hand terminal bar 18.

Suitable means for securing the heater 11 in proper operative position relatively to the device or the space in which it is to be located may be provided, as for instance, a 95 plurality of openings 27 in the upper portion of the cover member 14 to permit of securing the heater against a suitable supporting surface by means of bolts and nuts.

The device embodying my invention provides a relatively simple, rugged and compact structure for resiliently and removably supporting a plurality of refractory resistor rods. The amount of energy translated into heat may be easily and quickly varied by 100 employing either one or two refractory rods or by employing different rods, of different electrical resistances. For instance, it is possible to obtain standard carbonaceous resistor rods having a resistance of approxi- 105 110

mately 7000 ohms and if one of these rods is employed in the heater when used on 600 volt street-car circuit, approximately 50 watts will be translated into heat. If two 5 resistor rods are employed, substantially 100 watts will be translated into heat. This amount of energy translated into heat has been found sufficient to maintain the temperature of the usual controlling device located 10 beneath the floor of a street car at such temperature as will permit of the pneumatic devices operating properly even in relatively cold weather. The use of resistor rods having 15 lower electrical resistance will permit of the translation of a larger amount of energy without it being necessary to change any other part of the structure.

Various modifications may be made in the device embodying my invention without departing from the spirit and scope thereof, and I desire that only such limitations shall be placed thereon, as are imposed by the prior art or are specifically set forth in the appended claims.

25 I claim as my invention:—

1. In an electric heater, in combination, a pair of parallel, co-extensive, insulating bars, terminal members clamped between and supported by said bars, resistor supporting means carried by said terminal members, and refractory resistor rods supported by said resistor-supporting means.

2. In an electric heater, in combination, a pair of parallel, co-extensive, insulating bars, terminal members clamped between and supported by said bars, resilient current-conducting and resistor-supporting members carried by said terminal members, and re-

fractory resistor rods having their ends located in said resistor-supporting members. 40

3. In an electric heater, in combination, a pair of spaced, parallel, co-extensive, insulating bars, terminal members clamped between said bars at the ends thereof, a plurality of resilient terminal clips secured to the respective terminal members in back-to-back relation and a plurality of refractory resistor rods supported by said terminal clips. 45

4. In an electric heater, in combination, a base, a pair of spaced, parallel, co-extensive insulating bars having a narrow edge engaging said base, terminal members clamped between said bars at the ends thereof and extending therebeyond, a plurality of resilient terminal clips secured to each of the terminal members on opposite sides thereof, and a pair of refractory resistor rods removably supported at their ends by said terminal clips. 50

5. In an electric heater, in combination, a base, a pair of spaced parallel, co-extensive insulating bars each having a narrow edge engaging said base, means extending between said bars for securing them against said base, flat terminal members clamped between said bars at the ends thereof and extending therebeyond, a plurality of resilient terminal clips secured to each of the terminal members in back-to-back relation, a pair of refractory resistor rods removably supported at their ends by said clips and a cover member supported by said base. 60

In testimony whereof, I have hereunto subscribed my name this 17th day of August, 1922.

ORA A. COLBY.
